TORQUE TOOL WITH RATCHET SIGNAL

Herman W. Zimmerman, North Newington,
Conn.; Sylvia V. M. Zimmerman administratrix
of said Herman W. Zimmerman, deceased

Application April 21, 1944, Serial No. 532,109

1 Claim. (Cl. 81—52.5)

1

This invention relates to torque tools and particularly to hand tools having adjustable means to vary the force required to turn the handle or lever of a wrench or other tool relative to its screw engaging member or other work engaging member.

An object of the present invention is to provide a practical, simple and rugged torque tool such as a wrench that may be adjustable over a wide range and retain its adjustability over a long period of use.

Another object is to provide improved frictional retaining means for the hand lever relative to the work engaging member of the tool that may be adjusted to predetermined torques and which will retain any predetermined adjustment over long periods of use.

With the above and other objects in view the invention includes the features of construction and operation set forth in the following specification and illustrated in the accompanying drawing.

In the accompanying drawing annexed hereto and forming a part of this specification, I have shown the invention embodied in two different forms of tools but it will be understood that the invention can be otherwise embodied and that the drawing is not to be construed as defining or limiting the scope of the invention, the claim appended to this specification being relied upon for that purpose.

In the drawing:

Figure 1 is a longitudinal sectional view of a torque tool made in accordance with the invention:

Fig. 2 is a side elevation of a portion of the tool shown in Fig. 1.

Fig. 3 is a plan view of the portion of the tool shown in Fig. 2, and

Fig. 4 is a side elevation of another form of tool made in accordance with the invention.

In the above-mentioned drawing there have been shown two embodiments of the invention which are now deemed preferable, but it is to be understood that changes and modifications may be made within the scope of the appended claim without departing from the spirit of the invention.

Briefly, and in its preferred aspect, the invention may include the following principal parts: First, a hub member having engaging means thereon for the work piece such as a nut or screw to be tightened; second, a flange on said hub at an intermediate portion thereof; third, a nut threaded upon the hub member; fourth, a hand

2

lever one end of which fits over the intermediate portions of the hub member and is clamped frictionally between parts of or members on the hub; and fifth, a detent operated by relative movement of the hub member and hand lever.

Referring more in detail to the figures of the drawing, I provide a hub member 10 to which is frictionally connected a hand lever 11 of any convenient length in a manner presently to be described.

The hub member 10 comprises a short threaded member in the form of a stud having a screw or other work engaging end 12. As shown in Figs. 1 and 2, this end of the hub comprises a squared section adapted to fit within a squared recess in a screw or other member being tightened. At the opposite end of the member 10 is a threaded section over which fits a nut 13. At an intermediate portion of the hub member 12 is a flange 14 preferably formed integrally with the hub member.

On the hand lever 11 on opposite faces are collars 15 preferably pinned as shown to the lever 11 at one end. Extending through an opening within the hand lever 11 and collars 15 is the shank portion of the hub member 10. The outer face of one of the collars 15 bears against the flange 14. The opposite face of the opposite collar bears against a washer 16 on the shank portion of the hub. Between washer 16 and nut 13 a sealing washer 17 having a circular shroud may be mounted on the hub member to retain a sealing disc 18 threaded over the end of the hub member and disposed within the washer 17.

As shown in Figs. 1, 2 and 3, the periphery of the washer 16 is notched and engages a flexible strip member mounted within the hand lever and extending radially relative to the washer 16 and longitudinally of the hand lever. Relative movements, therefore, of the hand lever 11 and the hub member 10 produce an audible signal to indicate that the hand lever 11 is rotating relative to the hub member. To house one end of the flexible or resilient member 19, a block 20 may be secured to the hand lever having an opening extending longitudinally therethrough, one end of which frictionally engages and retains the member 19 in position and at the opposite end of the block the opening is widened to permit lateral movement of the member 19.

In Fig. 4 another form of torque tool is shown having a hub member 25 adapted for the insertion of a tool such as a screw driver or a socket fitting over the head of a screw or other part to be tightened. The upper end of this member 25

is reduced in diameter and threaded. The lower end of the tool handle 26 is provided with a yoke 27 on the opposite faces of which are secured collars 28 as by means of the pin 29. Above the upper collar is a washer 30, the periphery of which may be serrated if desired for engagement with a detent spring or other resilient member similar to that shown in Figs. 1, 2 and 3. A nut 31 above this upper washer enables the friction between the collars 28 and the hub member 25 and members mounted thereon to be regulated.

In either form of tool the torque applied by rotation of the lever 11 or handle 26 may be controlled by adjustment of the nut 13 or 31 and each tool, screw or other part tightened by operation of the forms of the invention will be drawn equally tight so long as the same adjustment of the nuts 13 and 31 is maintained. Preferably the collars 15 and 28 may be of brass or bronze and the parts on the hub member engaging these collars are of an iron or steel composition that under relatively high compressive stresses will not have their surfaces roughened by contact with the collars. The adjustment, therefore, for any torque will be maintained over a long period of use.

I claim:

A torque tool comprising in combination, a hub member having work engaging portions, a hand lever rotatable relative to said hub member, a flange on said hub member, a washer and a threaded member thereon, bearing collars on op-

posite faces of said hand lever of different material from the member on the hub and engaging said flange and washer respectively, means on said threaded means to vary the compression of said collars between said flange and washer, whereby the torque required to rotate said hand lever relative to said hub member may be regulated, ratchet means comprising a toothed wheel secured to the hub member and a resilient detent secured to said hand lever and engaging said toothed wheel to indicate when the frictional resistance has been exceeded and relative rotation of said hub member and lever is taking place, and sealing means for said threaded member in any predetermined adjusted position.
